UNITED STATES PATENT OFFICE.

JOHN W. GRAHAM, OF HINTON, WEST VIRGINIA.

LINOTYPE OR SLUG-CASTING MACHINE.

1,229,606.

Specification of Letters Patent. Patented June 12, 1917.

Application filed July 12, 1915. Serial No. 39,381.

To all whom it may concern:

Be it known that I, JOHN W. GRAHAM, a citizen of the United States, residing at Hinton, in the county of Summers and State 5 of West Virginia, have invented certain new and useful Improvements in Linotype or Slug-Casting Machines, of which the following is a specification.

My invention relates to typographical machines, such as linotypes of the original construction, wherein circulating matrices are released from a magazine, in the order in which their characters are to appear in print, and then assembled in line together 10 with expanding spacers, the composed line brought in contact with the face of a mold, the mold filled with molten metal, to form a line of type or slug against the matrices, which produce the type characters thereon, 15 and the matrices thereafter returned to the magazines, from which they were originally drawn.

More particularly it relates to that class of machines, having a series of magazines, 20 any one of which can be brought into operative position and locked therein; and to that end I provide a basket or rack to house, in this instance, eight magazines, but I do not limit myself as to the number, and I further 25 provide means by which the series can be lowered or raised by power mechanism, and such appliance is so arranged, that when the power raising or lowering device is put in motion, it first unlocks the magazines and 30 throws the channel entrance, escapement channel and key rods, back out of the way of the magazines, and then moves the series of magazines up or down, as desired, and particular stress is laid on the novel and 35 ingenious arrangement of the mechanism, it being impossible to move the magazine until the channel entrance and escapement channel is thrown out of the way, and also that all the operations are brought about 40 by turning the hand wheel. Turning the said hand wheel in the opposite direction causes the same series of operations, and reverses the direction of the travel of the basket and magazines, and further, that the 45 roller on the lower end of the lock operating rod, which roller rests in a depression in the operating cam, is so arranged that when the cam is turned back to resting position, said roller acts as a stop for such cam 50

and holds the cam from turning with the 55 vibration of the machine when the machine is in operation.

In the accompanying drawings I show my invention as an example, and in a preferred way and I wish it to be understood that I 60 do not limit myself to any form or embodiment, except in so far as such form or embodiment is specified in the claims. It is apparent that many changes and variations 65 will suggest themselves to those skilled in mechanical contrivances of this nature, and still not depart from the spirit or principle of this invention.

Referring to the drawings, Figure 1 is a side view of a portion of a linotype machine 70 having my invention applied thereto. Fig. 2 is a top view of the basket with a magazine in place, also showing the locking device. Fig. 3 is a side view of a section of a magazine showing a verge bar in place 75 housing a verge, and such verge in resting position, retaining a matrix in place, and also showing a key rod dotted in, to show the uppermost end slightly engaged in the slot in the verge bar. Fig. 4 shows a back 80 view of the rack or basket. Fig. 5 shows a section of the iron frame work on enlarged scale supporting the locking device. Fig. 6 shows the mechanism for the power raising and lowering device. 85

Referring to Fig. 1

A is the main arm of the machine frame. A¹ is a brace connecting the frame work of the basket support to the main arm A.

A² shows two slides on which the basket 90 travels, the front and rear sides being connected by a transverse bar upon which locking mechanism is mounted, as shown in Fig. 5.

A³ shows a brace to support the frame-work for the said basket.

B represents the individual basket in which the magazine rests.

B¹ shows a cross brace on the basket supporting frame.

B² shows the slides affixed to the basket.

B³ shows the threaded pipes which engage the screws.

B⁴ shows the screws for raising and lowering the basket.

B⁵ shows the bevel gears on the screws.

B⁶ shows the bevel gear on the cross shaft.

100

105

- B⁷ shows two cross shafts having on their ends the bevel gears B⁶.
- B⁸ shows supporting brackets for the magazines.
- 5 C shows a cam on the shaft C¹ to operate the locking device.
- C¹ shows the cross shaft which has on it the cam C.
- C² represents a crank to operate the cam.
- 10 C³ represents a roller on the end of the lock operating bar.
- C⁴ represents the lock operating bar.
- C⁵ represents the wedge on the upper end of the lock operating rod.
- 15 C⁶ represents the lock bars having end rollers R which engage the wedge C⁵.
- C⁷ is a coil spring to hold the lock bars in place when in resting position.
- C⁸ shows the forked end of the lock bar
- 20 which allows the channel entrance to be moved out without interfering with the lock.
- C⁹ is shown in Fig. 2 and represents the lock pin.
- D represents a shaft which carries the
- 25 friction clutch wheels to operate the power raising and lowering mechanism.
- Referring to Fig. 2
- C⁹ shows the lock pin.
- M shows a magazine.
- 30 K³ shows a hand wheel to operate the hand raising and lowering device.
- Referring to Fig. 3
- X shows a matrice in place.
- E shows a key rod.
- 35 E¹ shows a verge bar.
- E² shows the pins on which the verges are pivoted.
- E³ shows the verge.
- E⁴ shows the spring to hold the verge in
- 40 place.
- Referring to Fig. 4
- K² shows a sprocket wheel on the shaft B⁷.
- D⁹ shows a bevel gear on shaft B⁷.
- Referring to Fig. 5
- 45 F shows a plate or bar affixed to frame work A², to support the lock bar.
- F¹ shows a spring to hold the channel entrance in place.
- R shows the rollers on the lock bars C⁶.
- 50 Referring to Fig. 6
- D¹ and D² are friction bevel wheels on the shaft D.
- D³ shows a friction bevel wheel on the shaft D⁶.
- 55 D⁴ shows a slidable bearing housing the front end of the shaft D⁶.
- D⁵ shows a worm gear on the shaft C¹ to operate the friction wheel D³ against D¹ or D².
- 60 D⁶ is a shaft to operate the raising and lowering mechanism.
- D⁷ shows a bearing removably supporting the shaft D⁶ at its rear end.
- D⁸ shows a bevel gear on the shaft D⁶.
- 65 D⁹ shows a bevel gear on the shaft B⁷.
- K is a sprocket wheel on the shaft B⁷.
- K¹ is a chain connecting the sprocket K with the sprocket K².
- K² is a sprocket wheel on the rear shaft B⁷.
- In operating the machine, to raise or lower the magazines, the hand wheel or crank C² on the cam C, which in turn is on the shaft C¹, is turned, this operation turns the cam C, which cam when turned a sufficient distance, causes the roller C³ on the lower extremity of the lock operating rod C⁴, to rise, and forces the wedge C⁵ between the rollers R, thus forcing the two rods C⁶ apart one toward the front and the other toward the rear and releases the lock pins C⁹ from their socket holes Y. The front rod C⁶ is connected to the escapement channel and forces such channel outward and away from the magazines, such channel being connected by its casting T, to the key rods E, also draws the said key rods outward and away from said magazines. The rear bar C⁶ is connected to the channel entrance at the pin C⁸ by a forked end, and its movement forces such channel entrance outward and away from magazine, the forked end of said rod also allows the channel entrance to be turned out and returned to position without interfering with the lock, and the said channel entrance is held in place by the spring F¹. When the cam C is turned to a sufficient distance it operates the worm D⁵, on the shaft C¹ and throws the friction wheel D³ on the front end of the shaft D⁶, against one or the other of the moving friction wheels D¹ or D² on the shaft D, which shaft is already on all machines of the class described and is in continuous motion when machine is in operation, such engagement of friction wheels causes the shaft D⁶ to come into motion and this rotates the shaft B⁷ at the rear, by means of the intermeshed bevel gears D⁸ and D⁹, the rear shaft B⁷ is fitted with the sprocket wheel K² and connected to the frontal cross shaft B⁷, which is also fitted with a like sprocket wheel K; by the sprocket chain K¹, thus both cross shafts are brought into simultaneous motion, the two shafts B⁷ are connected at their ends to the screws B⁴, by bevel gears, thus the four screws B⁴ are brought into simultaneous motion, thus raising or lowering the basket. To operate the hand raising and lowering device, the hand wheel or crank C² is turned to unlock the magazine, the hand wheel K³ shown in Fig. 2 is then turned, this wheel being directly on the frontal shaft B⁷, and the motion is transmitted to the four screws B⁴ as above stated. When the crank C² is turned back to position the roller C³ drops into the depression in the cam C and the coil spring G throws the rod C⁴ downward thus releasing the rods C⁶ which are thrown back to resting position by their attendant

coil springs C', thus bringing the channel entrance and also the escapement channel and key rods back to operative position; also operating the lock pins C^o back into 5 their socket holes Y, and such lock pins C^o pass through the piece A² and into holes in the pieces B² thus locking the magazine firmly in position.

As above stated I have described my invention, and shown it by accompanying 10 drawings, merely as an example, and in a preferred way, and do not limit myself in any way, to any embodiment or form except in so far as such is specified in the claims.

15 Having described my invention its construction and operation what I claim and desire to secure by Letters Patent of the United States is as follows:

1. In a typographical machine the combination of a plurality of shiftable magazines, 20 a lock retaining the same against shifting, means to shift the said magazines, means to successively release the lock and operate the power shifting mechanism, and means for 25 applying the power including a movable shaft, a cam on the said shaft and means actuated thereby for releasing the lock.

2. In a typographical machine, the combination of a plurality of shiftable magazines, 30 a frame to house said magazines including a transverse bar, locking means adapted to lock the frame against shifting, lock releasing rods mounted on said transverse bar leading toward each other from the locks, 35 and a wedge-shaped cam member adapted to be inserted between the adjacent ends of said rods.

3. In a typographical machine the combination of a plurality of shiftable magazines, 40 a locking device to lock the said magazines against shifting, normally idle power driven shifting mechanism for the said magazines, means for applying the power including a movable shaft, a cam on the said shaft, and 45 connections for releasing the lock, between the cam and the lock.

4. In a typographical machine the combination of a plurality of shiftable magazines, a locking device to lock the said magazines 50 against shifting, normally idle power raising and lowering mechanism for the said magazines including, a clutch mechanism, a movable clutch applying shaft, a cam movable with the said shaft, and connections to 55 release the lock, between the cam and the lock.

5. In a typographical machine the combination of a plurality of shiftable magazines, a locking device to lock the said magazines 60 against shifting, and having a shiftable releasing rod, an additional shifting rod having a cam to actuate the first named rod, normally idle power driven raising and lowering mechanism, including a movable power 65 applying member, and means carried by the

said member to shift the aforesaid additional rod.

6. In a typographical machine the combination of a plurality of shiftable magazines, a rack or basket to house said magazines, 70 rack bars affixed to the said rack, a lock co-acting with the said rack bar to lock the rack against shifting, lock releasing rods leading toward each other from the locks, and a wedge or cam member, adapted to be 75 inserted between the meeting ends of the said rods.

7. In a typographical machine the combination of a plurality of shiftable magazines, 80 a rack or basket to house said magazines, escapement mechanism sufficient for each 85 magazine, and attached thereto at its frontal end, an escapement channel movable toward and away from the frontal end of the magazine, a plurality of escapement actuating rods made connected to the escapement channel, and the said rods and escapement channel movable toward and away from the magazine.

8. In a typographical machine the combination of a plurality of shiftable magazines, 90 each magazine fitted with escapement mechanism, an escapement channel movable toward and away from the frontal end of the magazine, a plurality of escapement actuating rods attached to the escapement channel and movable toward and away from the magazine, a lock retaining the magazine against shifting, a magazine entrance channel movable toward and away from the 100 magazine, and means to simultaneously release the lock and shift the actuating rods, and escapement channel, and the entrance channel away from the ends of the magazine. 105

9. In a typographical machine the combination of a plurality of shiftable magazines, 110 each magazine fitted with escapement mechanism; operating rods, and escapement channel movable toward and away from the magazine; a magazine entrance channel movable toward and away from the opposite end of the magazine, a lock to prevent the magazines from shifting, a lock releasing member, connections to retract the rods and 115 escapement channel situated between the lock releasing member and the escapement channel and rods, additional retracting connections between the lock releasing member and the magazine entrance channel, and power driven raising and lowering mechanism 120 for the magazines, operable upon the release of the lock.

10. In a typographical machine the combination of a plurality of shiftable magazines, 125 having escapement mechanism attached thereto, actuating rods and escapement channel movable toward and away from the said escapement mechanism, a wedge member for retracting the said rods 130

and escapement channel, means for shifting the magazines, including a movable member, a cam on the said member, and a rod carrying said wedge member bearing against 5 the said cam.

11. In a typographical machine the combination of a plurality of shiftable magazines, a lock for retaining the magazines against shifting, a shiftable rod for releasing the lock, means to shift the said rod, escapement mechanism attached to the magazines, key rods to actuate the escapement mechanism, and movable toward and away from the said escapement mechanism, and 10 means connected with said lock releasing rod to simultaneously release the lock and retract the rods from the magazine.

12. In a typographical machine the combination of a plurality of shiftable magazines, a lock to retain the magazines against shifting, and having a shiftable releasing rod, means to shift the said rod, escapement mechanism attached to the magazines, key rods to actuate the escapement mechanism, and movable toward and away from the 15 escapement mechanism, a guide member with which the key rods are engaged, and a link connecting the guide member and the aforesaid shiftable rod to move the escapement mechanism away from the magazine.

13. In a typographical machine the combination of a plurality of shiftable magazines, an inclined rectangular supporting frame having bearings at its four corners, 20 screws rotatably mounted in and rising from the said bearings, a shiftable magazine rack above the supporting frame, having nuts engaged by the aforesaid screws, and means to simultaneously operate all four screws.

14. In a typographical machine the combination of a rectangular supporting frame, bearings carried by the four corners thereof, screws rotatably mounted in and rising from the said bearings, bevel gears on the lower 25 ends of the said screws, a pair of shafts having their ends rotatably mounted at points adjacent the four bearings, additional bevel gears on the said shafts, intermeshing with the bevel gears on the screws, means to simultaneously rotate the two shafts and the 30 four screws, and a magazine rack having nuts engaged by the said screws.

15. In a typographical machine the combination of a plurality of shiftable magazines, a lock retaining the same against shift- 35

ing, normally idle power raising and lowering mechanism for the said magazines including a clutch mechanism, a movable clutch applying shaft, a cam movable with the said shaft, and connections between the 40 said cam and the lock to release the lock.

16. In a typographical machine the combination of a plurality of shiftable magazines, a lock retaining the same against shifting, a shiftable releasing rod, an additional 45 shifting rod, a cam attached thereto to actuate the first rod, normally idle power driven raising and lowering mechanism including a movable power applying member, and means carried by the said member to shift the 50 aforesaid additional rod.

17. In a typographical machine the combination of a plurality of shiftable magazines, escapement mechanism affixed to each magazine, operating rods and escapement 55 channel movable toward and away from the magazine, a magazine entrance channel movable toward and away from the opposite end of the magazine, a lock retaining the magazines against shifting, a lock releasing member, means to retract the rods and escapement channel situated between the lock releasing member and the escapement channel and rods, additional retracting connections between the lock releasing member and the 60 magazine entrance channel, and power driven raising and lowering mechanism for shifting the magazines operable upon the release of the lock.

18. In a typographical machine the combination of a plurality of shiftable magazines, escapement mechanism attached to each magazine, actuating rods and escapement channel movable toward and away from the said escapement mechanism, a 90 wedge shaped cam member for retracting said rods and escapement channel, means for shifting the magazines including a movable member, a cam on the said member, a rod bearing against said cam, said wedge shaped 95 cam member being connected to said rod and adapted to be inserted between the meeting ends of the aforesaid rods so as to retract the entrance and escapement channels.

In testimony whereof I affix my signature 105 in presence of two witnesses.

JOHN W. GRAHAM.
